COUNTERBORE

Filed, March 18, 1924

UNITED STATES PATENT OFFICE.

ALLEN C. DE ROCHEMONT, OF PORTSMOUTH, NEW HAMPSHIRE.

COUNTERBORE.

Application filed March 18, 1924. Serial No. 699,988.

To all whom it may concern:

Be it known that I, ALLEN C. DE ROCHEMONT, a citizen of the United States, residing at Portsmouth, in the county of Rockingham and State of New Hampshire, have invented new and useful Improvements in Counterbores, of which the following is a specification.

As heretofore constructed counterbores have commonly been provided with integral pilot members for engaging within holes formed of the proper size to receive them beyond the desired counterbored portion of the work to insure that the counterbored portions shall be coaxial with the remainder of the holes. Since the cutting edges of the tool are on its end inwardly of the pilot it has been customary to notch out the pilot adjacent the cutting edges so that the sharpening tool may traverse the full lengths of these cutting edges. This not only weakens the pilot, but as the tool is ground this notch is almost certain to be made deeper by the grinding tool, thus further weakening the tool so that breakage may result. The portion of the pilot thus notched also becomes less accurate as a guiding element as the cutting edges are ground back. For these reasons such tools have usually been rendered useless after comparatively little stock has been removed by sharpening. Each of these tools, also, is limited to a single size of hole and counterbore since the pilot is integral with the cutting portion.

This invention provides a construction wherein the objections above noted are eliminated, the pilot being a separate piece from the cutting portion and removable therefrom. Thus the pilot may be removed when the cutting edges of the counterbore portion are to be sharpened thus exposing the entire length of each cutting edge to the grinding operation and obviating injury to the pilot.

With this construction, also, pilots of various diameters may be assembled with counterbores of various diameters, thus obtaining a large number of proportions of counterbore to hole diameter with a comparatively small number of tool parts. The pilots may also be adjusted relative to the cutting portion to suit various conditions met with in practice, and if desired, they may be formed as working tools to perform other functions than merely to guide the counterbore cutting edges.

For a more complete understanding of this invention reference may be had to the accompanying drawings in which—

Figure 1 is a side elevation of a counterbore constructed according to this invention.

Figure 2 is a side elevation of the end portion thereof, the pilot having been removed.

Figure 3 is a section on line 3—3 of Figure 2.

Figure 4 is a side elevation of the pilot member.

Figure 5 is a section on line 5—5 of Figure 4.

Figure 6 shows the pilot made in the form of a drill.

Figure 7 shows the pilot adjusted to form a depth gage for the counterbore.

Figure 8 shows a pilot of relatively large diameter, the counterbored hole being diagonal to the surface of the work.

Figure 9 shows the pilot extended to bear within the hole when the counterbored portion has been cored out.

Figure 10 shows the pilot formed as a rose reamer.

Figure 11 is a side elevation showing a four-bladed counterbore.

Figure 12 is a section on line 12—12 of Figure 11.

Figure 13 shows a modified construction particularly designed for cutting tube holes in boiler tube sheets.

Referring first to Figures 1 to 5, 1 indicates a blade member having cutting edges 2 formed at one end and a shank 3 of any suitable form for engagement with driving mechanism at the other. Intermediate the side edges of the blade portion 2 a channel 4 is formed longitudinally on each side thereof and centrally of this channel a slot 5 is cut through this piece.

The pilot member comprises a cylindrical end portion 6 having a shank 7 extending therefrom slotted out to form a pair of spaced jaws 8, the space 9 therebetween being of sufficient width so that the jaws 8 may engage opposite sides of the blade member sliding within the opposed channels 4 on opposite sides thereof. Adjacent to their ends the jaws 8 are perforated at 10 for the reception of a tightening bolt 11 which may extend through the slot 5 and when tightened clamps the jaws 8 firmly to the blade member 1 with the cylindrical portion 6 extending beyond the cutting

edges 2 as shown in Figure 1. A plurality of pilot members having cylindrical portions 6 of different diameters may be employed with each blade member 1, the jaws 8 in all these forms being of such size as to fit within the channels 4.

When it is desired to sharpen the cutting edges 2 the pilot member is removed, whereupon the grinding tool may act on the entire cutting edge which is left free from obstruction as will be evident from an inspection of Figure 2. The pilot member may then be assembled with the blade member, the jaws 8 being clamped in position in the channels 4 within which they fit sufficiently closely so that the pilot portion 6 is in correct axial alinement with the blade portion. By means of the tightening bolt 11 passing through the slot 5 the distance to which the pilot portion 6 extends beyond the cutting edges 2 may be adjusted as may be desired. For example, it may be adjusted to form a depth gage to determine the depth of the counterbore as is illustrated in Figure 7 in which the pilot portion 6 passes entirely through the work 20 when the counterbore cutting edges 2 have reached their proper depth from the upper face of the work.

The pilot portion 6 may also be extended so that it bears firmly within the guiding hole 21 of work in which the counterbore portion has been cored out as shown in Figure 9 so that the pilot may have bearing within the hole 21 before the cutting edges 2 have begun to act on the work. By this means proper positioning of the counterbored hole is insured even though the counterbored portion may be so deep as to make it impossible for the pilot as ordinarily constructed to reach the guiding hole with which the counterbore is desired to be in axial alinement before the edges 2 are brought into action.

In Figure 8 the pilot portion 26 is shown as of a larger diameter than the pilot portion 6 of Figures 1, 4, 7 and 9, this illustrating different proportions of counterbored diameter and pilot hole diameter which may be effected by the construction of this invention. This figure also illustrates the manner in which the pilot portion 26 is properly guided within its guide hole diagonally to the face of the work.

In Figures 6 and 10 the pilot is shown as a cutting tool instead of merely as a guide member, in Figure 6 this pilot portion 28 being formed as a bit to bore its own hole in the work and in Figure 10 the pilot portion 29 being formed as a rose reamer to enlarge the hole within which it is guided.

In Figures 11 and 12 is shown a construction in which the blade member is provided with four blades each having a cutting edge at its end. These four blades are indicated at 30. In this construction the pilot member

has a pilot portion 31 and spaced jaws 32 which engage within the opposite angles between pairs of blades 30, the jaws being held in clamped position by means of a clamping bolt 33 extending through a slot 34 through the blade member.

Still another embodiment of this invention is the special tool shown in Figure 13, particularly intended for cutting tube holes in boiler tube sheets. As therein shown the guiding pilot portion 35 of the pilot member is of comparatively small diameter, the jaws 36 being much larger and fitting within correspondingly wide channels in the blade member 37. This blade member is extended to form cutting edges 38, intermediate these edges the blade member is cut away as shown by the dotted line at 39. Each cutting edge 38 is therefore considerably narrower than the distance between its outside diameter and that of the pilot portion 35. This pilot portion engages within a pilot hole formed within the boiler tube sheet and the blades 38 cut in an annular path coaxial with the pilot 35 through the boiler sheet, thus leaving a central uncut ring or washer portion 39 which drops out. This avoids the necessity of cutting away the entire mass of metal within the desired diameter of the hole for the boiler tube, this representing a material saving in power required to cut the tube holes.

Having thus described certain embodiments of this invention it should be evident to those skilled in the art that various changes and modifications might be made therein without departing from its spirit or scope as defined by the appended claims.

I claim:

1. A device of the class described comprising a blade member having end cutting edges and longitudinally slotted back of said edges, a pilot member slotted from one end to form a pair of jaws to take over said blade member, and means engaging the free ends of said jaws and passing through the slot of said blade member to clamp said pilot member to said blade member in adjustable axial relation.

2. A device of the class described comprising a blade member having axially arranged channels on opposite faces and cutting edges at one end, a pilot member having spaced jaws engaging in said channels and projecting beyond said cutting edges, and means for fixing said jaws in said channels.

3. A device of the class described comprising a blade member having axially arranged channels on opposite faces and slotted through a portion of its length within said channels, a pilot member having a substantially cylindrical head at one end and slotted to form a pair of opposed jaws fitting within said channels, and a clamping

bolt passing through perforations adjacent to the free ends of said jaws and through said slot for fixing said pilot member to said blade member in longitudinally adjustable substantially coaxial relation.

4. A device of the class described comprising a blade member having axially arranged channels on opposite faces and cutting edges at one end of said blade member,

a pilot member having a pilot portion at 10 one end and a pair of jaws at the opposite end formed to engage in said channels, said pilot and jaw portions being of different diameters, and means for fixing said jaws in position.

In testimony whereof I have affixed my signature.

ALLEN C. DE ROCHEMONT. [L. S.]
